US00D825760S

(12) **United States Design Patent** (10) **Patent No.:** **US D825,760 S**
Brönnimann et al. (45) **Date of Patent:** **** Aug. 14, 2018**

(54) **IMPLANT**

(71) Applicant: **OSTOMYCURE AS**, Oslo (NO)

(72) Inventors: **Benedict Brönnimann**, Penthaz (CH);
Mats Erik Kindahl Cardell,
Sollentuna (SE); **Jan Anders Berglund**,
Järfälla (SE); **Robert Axelsson**, Gränna
(SE)

(73) Assignee: **Ostomycure AS**, Oslo (NO)

(**) Term: **15 Years**

(21) Appl. No.: **29/626,271**

(22) Filed: **Nov. 15, 2017**

Related U.S. Application Data

(62) Division of application No. 29/551,253, filed on Jan. 12, 2016, now Pat. No. Des. 816,842, which is a division of application No. 29/471,220, filed on Oct. 29, 2013, now Pat. No. Des. 752,750.

(57) **CLAIM**

The ornamental design for an implant, as shown and described.

DESCRIPTION

FIG. 1 is a top perspective view of an implant according to the present invention.

FIG. 2 is a top view thereof.

FIG. 3 is a bottom perspective view thereof.

FIG. 4 is a bottom view thereof.

FIG. 5 is a front side view thereof.

FIG. 6 is a back side view thereof.

FIG. 7 is a left side view thereof; and,

FIG. 8 is a right side view thereof.

The broken line showing is included for the purpose of illustrating unclaimed subject matter and forms no part of the claimed design.

1 Claim, 8 Drawing Sheets
